UNITED STATES PATENT OFFICE.

WILLIAM R. TEMPLETON, OF BOSTON, MASSACHUSETTS, ASSIGNOR TO TEMPLETON MANUFACTURING COMPANY, OF BOSTON, MASSACHUSETTS, A CORPORATION OF MAINE.

VALVE MECHANISM.

SPECIFICATION forming part of Letters Patent No. 790,536, dated May 23, 1905.

Application filed July 23, 1904. Serial No. 217,766.

To all whom it may concern:

Be it known that I, WILLIAM R. TEMPLETON, a citizen of the United States, and a resident of Boston, county of Suffolk, State of Massachusetts, have invented an Improvement in Valve Mechanism, of which the following description, in connection with the accompanying drawings, is a specification, like characters on the drawings representing like parts.

This invention has for its object the production of simple and efficient valve mechanism for water, steam, or other fluid motors whereby the admission and discharge of motive fluid from the motor-cylinder are effected without the use of packing, stuffing-boxes, and similar leak-preventing devices. The construction and arrangement of the valve mechanism are such that the pressure of the incoming motive fluid serves to tightly seat and hold the valve within its casing or shell.

The various novel features of my invention will be fully described in the subjoined specification and particularly pointed out in the following claims.

I have herein chosen to illustrate my invention in connection with a water-motor air-compressing apparatus, for which my invention is particularly well adapted; but it is to be understood that my invention is in no sense restricted to such use or application, nor to the control of any particular motive fluid.

Figure 1 is a top or plan view of a duplex air-compressor with the cylinders of the motor provided with valve mechanism embodying one form of my present invention. Fig. 2 is a partial sectional view on the irregular line 2 2 2, Fig. 1, looking toward the right, showing very clearly the construction of the valve mechanism. Fig. 3 is a side elevation of the valve-shell, showing the admission and exhaust ports therein. Figs. 4 and 5 are side elevations of the valve, the latter being turned one-quarter round in Fig. 5 from the position shown in Fig. 4. Figs. 6 and 7 are enlarged horizontal sections through the admission and exhaust ports or openings, respectively, of the shell and valve when the valve is set in

one position; and Figs. 8 and 9 are similar views, but showing the valve set in its other position to admit motive fluid to the outer end 50 of the motive cylinder and exhaust from its inner end viewing Fig. 1.

Referring to Fig. 1, A A' represent two air-compressing cylinders provided with suitable valves for inlet and egress of air and forming 55 no part of my invention, said cylinders being rigidly mounted on a base or bed B, and two motor-cylinders C C' are mounted on the bed in axial alinement with the compressing-cylinders, the piston-rods a a' having suitable 60 pistons (not shown) within the motor and compressing cylinders, respectively. The motor-cylinders are connected by a chambered casting C^X, having an inlet-port c', opening into a compartment c², (see Fig. 2,) and an outlet 65 or discharge port c³, which communicates with the two lower compartments c⁴ in the casting. Adjacent each cylinder a hole is bored through the casting from top to bottom, as at c⁵, Fig. 2, each hole communicat- 70 ing with the compartments c² and c⁴ of the casting on the one side and on the other side communicating with the admission and exhaust passages of the adjacent motor-cylinder. The admission-passages for the cylinder C are 75 shown at c¹⁰ c¹¹ on dotted lines, Fig. 1, and the end of one of the exhaust-passages is shown at c¹² in Fig. 2, the outer ends of the exhaust-passages being in practice below the corresponding ends of the admission-passages. A 80 valve case or shell, shown as a tube 1, is made to fit tightly into the hole c⁵, which is enlarged at its upper end to form a shoulder 2, Fig. 2, on which rests an external annular flange 3 on the shell, the bottom of the latter 85 having a central opening, so that an annular thrust-bearing 4 is presented at the lower and smaller end of the shell, the shell being slightly tapered internally. A threaded cap 5 screws into the casting C^X and closes the upper end 90 of the hole c⁵, forming a supply-chamber 6, Fig. 2, which is located at the upper end of the shell.

Referring to Fig. 3, I have shown two elong-

gated and longitudinally-extended ports 7 7^x in the shell near its upper end, which ports register with the ends of the admission-passages $c^{10} c^{11}$ of the cylinder when the shell is 5 in place, and such ports I term "admission-ports." These ports are near each other, and below them I have arranged two similar ports 8 8^x to register with the cylinder exhaust-passages c^{12} , while a much larger port 9 is 10 formed in the shell opposite the ports 8 8^x. These latter I have for convenience termed "auxiliary exhaust-ports" of the shell and the port 9 the "main exhaust-port" thereof. 15 Packing, stuffing-boxes, and similar devices for preventing valve-leakage have been largely used; but in my present invention I have constructed the valve mechanism in such manner that the use of such antileak devices is obviated. To this end the valve proper is 20 made as a metallic elongated plug 10, shown separately in Figs. 4 and 5 and tapered to correspond to the internal taper of the shell, the latter and the plug being preferably ground to secure a fluid-tight fit. The valve is rotatably mounted in the shell, and its lower end is seated on the annular thrust-bearing 4, the valve being reduced in diameter and prolonged to form a spindle 11, which is adapted to pass 25 easily through the center of the bearing and project beyond the shell, as in Fig. 2. At its upper end the valve is cored out to form a chamber 12, open at its upper end, and thus in continuous communication with the supply-chamber 6, and two like openings 13 13^x are 30 formed in its side walls diametrically opposite each other, as will be apparent from Figs. 6 and 8. These openings are at such a height that when the valve is oscillated they will alternately coöperate with the admission-ports 7 7^x of the shell, as will be manifest. 35 Below the chamber and wholly separate therefrom a large transverse passage 14 is formed in the valve, extending diametrically therethrough and adapted to connect the main exhaust-port 9 with either of the auxiliary ports 8 8^x of the shell.

Referring to Fig. 2 it will be seen that the incoming motive fluid passes from the compartment c^2 into the supply-chamber 6 and 40 fills the valve-chamber 12, the pressure of the fluid acting upon the valve in the direction of its length to maintain it seated fluid-tight upon the thrust-bearing 4 without any packing, glands, or stuffing-boxes. The fit between the shell and valve prevents any leakage therebetween. Now when the valve is 45 turned into the position shown in Figs. 2, 6, and 7 the fluid will pass from chamber 12, through the opening 13 and admission-port 7, to the cylinder admission-passage c^{10} , and the fluid will be admitted at one side of the piston to move the piston-rod a to the left, Fig. 1, while the exhaust passes through passage 50 c^{12} and port 8^x to the passage 14 and thence

through the main exhaust-port 9 into the exhaust-compartment c^4 of the casting C^x. The valve is then turned by any suitable mechanism into the position shown in Figs. 8 and 9, shutting ports 7 and 8^x and connecting port 7^x by opening 13^x with the chamber 12, to 55 admit fluid through passage c^{11} to the left-hand end of the cylinder. At the same time the passage 14 connects the main exhaust-port 9 and auxiliary port 8 to exhaust the right-hand end of cylinder C, Fig. 1, the several 60 ports in the valve being so located and of such size that the desired admission and exhaust are secured. The width of the port 9 is sufficient to register with the valve-passage 14 when the latter at its opposite end coöperates 65 with either auxiliary port 8 or 8^x, and when the valve is turned there will be an interval when both of the latter ports are closed by the solid wall of the valve.

Any suitable valve-operating mechanism 70 may be employed, and I have shown in Fig. 1 a simple and effective form of such mechanism, which I will describe briefly. Pinions 20 30, Fig. 2, are secured to the projecting valve-spindles 11 in such manner that the pinions will be in different horizontal planes, said pinions meshing, respectively, with segmental gears 21 31, mounted to rock on an upright port b on the bed B. A link 22 pivotally connects the segment-gear 21 with the 75 end of a lever 23 fulcrumed on a port b^x on the bed, the opposite outer end of the lever being pivotally connected with the piston-rod a' by a coupling 24. Similarly a link 32 connects the segment-gear 31 with a lever 33, 80 also fulcrumed on the port b^x , the lever being connected at its outer end with the piston a by a suitable coupling 34. The reciprocatory movement of each piston operates 85 through the described connections to oscillate the valve controlling the admission and exhaust of the other motor-cylinder, as will be manifest, the relation between the two valves and their actuating devices being such that one piston-rod will be moving when the other 90 piston-rod is changing its direction of movement, so that the two motor-cylinders cannot 95 get on dead-center.

By the valve construction herein described 100 the pressure of the incoming motive fluid always maintains the valve properly and tightly seated, preventing leakage or lifting of the valve at the time of exhaust from back pressure; secondly, the wear on the side walls of the shell is practically inappreciable, as 105 the thrust-bearing at the bottom takes up the pressure of the valve, the bearing presenting sufficient area for the purpose, and the friction between the valve and the sides of the shell is reduced to a minimum; thirdly, neither 110 the valve itself nor the valve-stem or spindle requires any packing or stuffing; finally, the 115 number and arrangement of ports is such that 120 125

a single valve controls the entire admission and exhaust for the motor-cylinder.

Various changes or modifications in details may be made in the construction herein shown and described without departing from the spirit and scope of my invention.

Having described my invention, what I claim, and desire to secure by Letters Patent, is—

10 1. Valve mechanism comprising an elongated shell, a supply-chamber located at one end thereof and a thrust-bearing at its opposite end, said shell being provided with lateral admission-ports and exhaust-ports, a valve 15 rotatably mounted in the shell and seated at one end on the thrust-bearing, a chamber in the opposite end of the valve in continuous communication with the supply-chamber and having openings in its walls to coöperate with the admission-ports, and a transverse passage 20 through the valve and located between the bottom of the valve-chamber and the bearing end of the valve, to coöperate with the exhaust-ports of the shell, the pressure of the 25 motive fluid in the supply-chamber acting longitudinally of the valve to maintain the same seated upon the thrust-bearing.

2. Valve mechanism comprising an elongated, internally - tapering shell, a supply-chamber located at its larger end and a thrust-bearing at its opposite end, said shell being provided with lateral admission-ports, and exhaust-ports on opposite sides of the shell, a correspondingly - tapering valve rotatably 30 mounted in the shell and having its smaller, flat end seated on the thrust-bearing, an open-ended chamber in the opposite end of the valve in continuous communication with the supply-chamber and having openings in its walls to coöperate with the admission - ports, and a transverse passage through the valve below the bottom of the chamber therein, to coöperate with the exhaust-ports of the shell, the 35 pressure of the motive fluid in the supply-chamber acting longitudinally of the valve to maintain the same seated upon the thrust-bearing and in contact with the tapering walls of the shell.

3. Valve mechanism comprising an elongated, internally - tapering shell, a supply-chamber located at its larger end and a thrust-bearing at its opposite end, said shell being provided with lateral admission-ports near its upper end and a main and two auxiliary exhaust-ports near its lower end, a correspondingly-tapered, solid valve rotatably mounted 40 in the shell and having its smaller, lower end seated on the thrust-bearing, an open-ended chamber in the upper end of the valve opening into the supply-chamber and having openings in its side walls to coöperate with the admission-ports, and a transverse, diametral passage through the valve below the bottom of the chamber therein to intermittently estab-

lish communication between the main and either auxiliary exhaust-port, the pressure of the motive fluid in the supply-chamber acting upon the upper end of the valve to maintain the same seated upon the thrust-bearing and in contact with the tapering walls of the shell. 65

4. Valve mechanism comprising an elongated, internally - tapering shell, a supply-chamber located at its larger end and an annular thrust-bearing at its opposite end, said shell being provided with two adjacent admission-ports near its upper end and with exhaust-ports on opposite sides near its lower end, a correspondingly-tapered plug-valve rotatably mounted in the shell and seated at its lower end upon the thrust-bearing, a valve-spindle 70 extended through the latter and projecting beyond the shell, an open chamber in the upper end of the valve in continuous communication with the supply-chamber and having openings in its side walls to intermittently coöperate with the admission-ports of the shell, said valve having a diametrical passage extended through it below the chamber to at times connect exhaust-ports on opposite sides of the shell, the pressure of the motive fluid 75 in the supply-chamber acting upon the valve longitudinally to maintain it seated upon the thrust-bearing and fluid-tight in the shell without packing, and valve-actuating means connected with the projecting end of the valve-spindle. 80

5. Valve mechanism comprising an internally-tapered shell, a supply-chamber located at its upper end and a thrust-bearing formed by its lower end, said shell being provided with lateral admission and exhaust ports, a correspondingly - tapered valve rotatably mounted within the shell and seated at its lower end upon the thrust-bearing, the upper end of the valve receiving the pressure of the motive fluid in the supply-chamber, to maintain the valve fluid-tight within the shell without packing, passages in the valve to intermittently connect the supply-chamber and the admission-ports of the shell, and a separate passage in the valve to coöperate with the exhaust-ports of the shell. 90

6. The combination with a motor-cylinder having admission and exhaust passages, of controlling-valve mechanism comprising a fixedly-mounted, internally-tapering shell, a supply-chamber located at its upper end and said shell having two adjacent admission-ports registering with the admission-passages of the cylinder, a main and two auxiliary exhaust-ports, the latter registering with the cylinder exhaust-passages, and an annular thrust-bearing at the lower end of the shell, a correspondingly-tapered plug-valve rotatably mounted in the shell and seated at its lower end upon the thrust-bearing, said valve having an open chamber in its upper end communicating with the supply-chamber and provided in its side 100 105 110 115 120 125

wall with openings to intermittently coöperate with the admission-ports, the valve having a transverse passage therethrough below the chamber, to at times connect the main and one of the auxiliary exhaust-ports of the shell, a valve-spindle projecting through the thrust-bearing and beyond the shell, and valve-actuating means connected with the spindle.

In testimony whereof I have signed my name to this specification in the presence of two subscribing witnesses.

WILLIAM R. TEMPLETON.
